(57) **CLAIM**

The ornamental design for a bag, as shown and described.

DESCRIPTION

FIG. 1 is a perspective view of a first embodiment of a bag, showing my new design;

FIG. 2 is a front view of the first embodiment;

FIG. 3 is a rear view of the first embodiment;

FIG. 4 is a right side view of the first embodiment;

FIG. 5 is a left side view of the first embodiment;

FIG. 6 is a top view of the first embodiment;

FIG. 7 is a bottom view of the first embodiment;

FIG. 8 is a perspective view of a second embodiment of a bag, showing my new design;

FIG. 9 is a front view of the second embodiment;

FIG. 10 is a rear view of the second embodiment;

FIG. 11 is a right side view of the second embodiment;

FIG. 12 is a left side view of the second embodiment;

FIG. 13 is a top view of the second embodiment; and,

FIG. 14 is a bottom view of the second embodiment.

The broken lines shown depict environmental subject matter, are included for the purpose of illustrating the unclaimed portions of the bag and form no part of the claimed design.

1 Claim, 10 Drawing Sheets
